UNITED STATES PATENT OFFICE.

JAMES AUGUSTUS SULLIVAN, OF VICTORIA, BRITISH COLUMBIA, CANADA.

AUTOMATIC SHIP'S-TELEGRAPH ALARM.

1,099,673.

Specification of Letters Patent.

Patented June 9, 1914.

Application filed February 26, 1913. Serial No. 750,867.

To all whom it may concern:

Be it known that I, JAMES AUGUSTUS SULLIVAN, of the city of Victoria, Province of British Columbia, Dominion of Canada, have invented certain new and useful Improvements in Automatic Ships'-Telegraph Alarms; and I do hereby declare the following to be a full, clear, and exact description of the same.

10 My invention relates to improvements in automatic ships' telegraph alarms, and the object of the invention is to devise audible means for indicating to the ship's engineer when the position of the way-shaft does not correspond to the position indicated by the ship's telegraph, and it consists essentially of the ship's telegraphic apparatus provided with a pair of contacts one on the astern side of the device, and one on the ahead side, a core of insulating material supported in a suitable casing, a plunger supported within the core and forming a movable contact, connecting means between the plunger and the way-shaft and a stationary contact supported by the core and with which the plunger contact is permanently in engagement. A pair of contacts also carried by the core with which the plunger is alternately in engagement. A circuit wire 20 leading from the permanent contact through a bell and battery, to a ground contact on the telegraph device, and circuit wires connecting the two remaining contacts with the contact plates on the telegraphic device, all as 25 hereinafter more fully set forth and described in the accompanying specification and drawings.

In the drawings: The figure represents a partially diagrammatic and partially sectional view of my device.

In the drawings like characters of reference indicate corresponding parts.

A is the telegraph device constructed in the usual manner with the ahead indications on one side of the dial, and the astern indications on the other side of the dial, and the usual indicating pointer A³ operated by a handle in the pilot house. The pointer A³ of the device is adapted to serve as a contact finger.

A⁴ is an arc shaped contact plate located on the ahead side of the telegraph device

A. The plate A⁴ is provided with a terminal A⁵.

A⁶ is a similar plate located on the astern side of the telegraph device A, and provided with contact post A⁷.

It will be readily understood that when the handle is swung in the direction indicated by the arrow that is toward the ahead portion, the pointer A³ will engage with the contact plate A⁴, and when the handle is swung in the opposite direction to that indicated by the arrow, or toward the astern portion the pointer carried thereon will engage the contact plate A⁶.

5 is a casing secured by suitable means to a portion of the engine column or other convenient place. The casing 5 is insulated on its inner side and is provided with an opening A⁸, which is threaded to receive a conduit for carrying wires.

B is a core of insulating material secured within the lining A⁹ of the casing 5 by screws B¹, and B² is an orifice extending vertically through the center of the core B, and B³, B⁴ and B⁵ are openings extending from the periphery of the core into the vertical orifice B².

B⁶ is a vertical channel extending from the top of the core into the opening B³. B⁷ is a similar channel extending from the top of the core into the opening B⁵.

C is a contact finger secured to the outside of the core in the channel B⁶ by screws C¹. The lower end of the finger extends horizontally through the opening B³ and is provided with upturned end C². D is a similar contact to the contact C, the contact D extending through the opening B⁴ into the center orifice B². E is a contact also similar to the contact C and extending through the orifice B⁵.

F is the way shaft.

G is a vertical plunger rod having vertical bearing formed by a stuffing box 5¹ on the casing 5.

G¹ is a link connected at its upper end by knuckle joints G² to the plunger rod G, the lower end of the link G¹ being connected by knuckle joints G³ to the way shaft F, or corresponding element in case of a turbine or other engine. The link G¹ is made with a turnbuckle having right and left hand

threads with a lock nut on one end, this allows for adjusting position of movable contact 1.

H is an electric bell.

H¹ is a battery.

2 is a wire leading from the contact C to and through the bell H and the battery H¹ to the ground circuit 3 connected to the telegraph device. It might be advisable to connect this wire direct to spindle which carries pointer A² in telegraph A, but this might not be necessary in all cases. If pointer A² is already grounded through metallic contact, it will only be necessary to run wire 2 to ground after passing bell H and battery H¹.

4 is a wire leading from the contact E to the terminal post A⁵.

6 is a wire leading from the contact D to the terminal post A⁷.

I is a removable contact, secured to the plunger rod G and comprising an insulating sleeve I¹, insulating washers I² and I³ between which extends the metallic contact sleeve I⁴.

I⁵ and I⁶ are metallic washers held against the washers I² and I³ by the lock nuts I⁷ and I⁸ threaded on to the plunger rod G.

It will be understood that the contact sleeve I⁴ is always in contact with the contact finger C and is carried alternately into contact with the contact fingers D and E according to the position in which the way shaft is set.

All wires leading from box 5 to telegraph A and to bell etc. should be carried through conduits. The bottom of box 5 is made detachable to allow placing core inside.

In the position shown in the drawing, 43 the way shaft is set in the ahead position. Should, however, the telegraph indicator be set to indicate the astern position, the circuit will be closed, through stationary contact finger C, through the wire 2 and bell

H to the battery H¹, and from the battery H¹ to the ground contact 3, indicating pointer A³, contact plate A⁴, wire 6, contact finger D and movable contact sleeve I⁴. By this means the bell H is rung, thereby 59 warning the engineer that the way shaft is set in the wrong position and does not correspond to the position indicated by the telegraph indicator.

When the way shaft is set to the astern 55 position, the movable contact 14 will be carried inwardly in the core B² so as to electrically connect the fingers C and E.

If when the way shaft is in this position 60 the telegraph indicator indicates ahead, a circuit will be closed through contact fingers C, through wire 2, bell H, to the battery H¹, and from the battery H¹ through the ground contact 3, indicating pointer A³, contact plate A⁴, wire 4, contact finger E 65 to and through the movable contact I⁴. In

this position of the way shaft, the bell H is also rung, indicating that the way shaft is wrongly set. Of course, if the way shaft is rightly set, the circuit through the bell is kept open, and therefore the bell does not ring.

From this description it will be seen that I have devised a very simple device, whereby the engineer will be immediately warned if a mistake is made in setting the way shaft, 75 such audible signal immediately calling his attention to the telegraph indicator, thereby enabling him to immediately rectify his error.

While I have shown the indicating finger A¹ adapted for uses as a contact, it is obvious that if desired a separate contact might be provided.

In turbines a way shaft would not be employed, but in such case the movable contact would be connected to the corresponding part of the engine controlling means.

What I claim as my invention is:—

1. An automatic ship's telegraph alarm of the class described comprising a dial, indicating ahead and astern positions, a pair of contacts thereon, one located at the astern position and one at the ahead position, an indicating pointer on said dial, such pointer being adapted to act as a contact, a casing consisting of lateral and top sides, such top side having an orifice therethrough, a cover adapted to be secured to the bottom of said casing and having an orifice located in the center thereof, an insulating member extending on and around the inner face of such casing, contact fingers located in such casing, a movable contact designed to engage with such contact fingers, a bell, a battery, circuit wires connecting the bell and battery to the contact fingers and to the said dial, contact plates and means of operating the movable contact in such casing, as and for the purpose specified.

2. An automatic ship's telegraph alarm of

the class described comprising a dial indicating ahead and astern positions, a pair of contacts thereon, one located at the astern position and one at the ahead position, an indicating pointer on said dial, such pointer being adapted to act as a contact, a casing consisting of lateral and top sides, such top side having an orifice therethrough, a cover adapted to be secured to the bottom of said casing and having an orifice located in the center thereof, an insulating member extending on and around the inner face of such casing, an insulating core in said case having an orifice through its longitudinal axis and radially extending apertures extending from its inner to its outer periphery, means for securing such core in position, contact fingers designed to operate in said apertures, a movable core having a metallic contact on and extending around its

outer periphery, means of securing such contact in position, a plunger rod connected at one end to said removable core, circuit wires connecting the said contact fingers to 5 a bell, a battery and the said dial, contact plates and means of operating the said plunger rod, as and for the purpose specified.

3. An automatic ship's telegraph alarm of the class described comprising a dial indicating ahead and astern positions, a pair of contacts thereon, one located at the astern position and one at the ahead position, an indicating pointer on said dial, such pointer being adapted to act as a contact, a casing 15 consisting of lateral and top sides, such top side having an orifice therethrough, a cover adapted to be secured to the bottom of said casing and having an orifice located in the center thereof, an insulating member extending on and around the inner face, an insulating core in said casing having an orifice through its longitudinal axis and radially extending apertures connecting its 20 inner and its outer periphery, means of securing such core in position consisting of screws designed to pass through the casing and engage with the said insulating member and insulating core, contact fingers designed to operate in the said apertures, a movable 25 core having metallic contact on and extending around its outer periphery, means of securing such contact in position, a plunger rod connected at one end to the said removable core, circuit wires connecting the said 30 fingers, a bell, a battery and the said dial, contact plates and means for operating the plunger rod, as and for the purpose specified.

4. An automatic ship's telegraph alarm of 40 the class described comprising a dial indicating ahead and astern positions, a pair of contacts thereon, one located at the astern position and one at the ahead position, an indicating pointer in said dial, such pointer 45 being adapted to act as a contact, a casing consisting of lateral and top sides, such top side having an orifice therethrough, a cover adapted to be secured to the bottom of said casing and having an orifice located in the 50 center thereof, an insulating member on and extending around the inner face of such casing, an insulating core in said casing having an orifice through its longitudinal axis and radially extending apertures connecting its 55 inner and its outer periphery, screws designed to engage with the casing and the said insulating core, contact fingers de-

signed to operate in the said apertures, a movable core having a metallic contact on and extending around its outer periphery, 60 means of securing such contact in position, a plunger rod connected at one end to the said removable core, a gland secured to the bottom cover of casing, a connecting rod pivotally attached at one end to the way shaft 65 and at the other end to the said plunger rod, circuit wires connecting the said contact fingers, a bell, a battery and the said dial, and means of adjusting the contact with the movable core, as and for the purpose 70 specified.

5. An automatic ship's telegraph alarm of the class described comprising a dial indicating ahead and astern positions, a pair of contacts thereon, one located at the astern 75 position and one at the ahead position, an indicating pointer in said dial, such pointer being adapted to act as a contact, a casing consisting of lateral and top sides, such top side having an orifice therethrough, a cover 80 adapted to be secured to the bottom of said casing and having an orifice located in the center thereof, an insulating member on and extending around the inner face of such casing, an insulating core in said casing 85 having an orifice through its longitudinal axis and radially extending apertures connecting its inner and its outer periphery, screws designed to engage with the casing and the said insulating core, contact fingers 90 designed to operate in the said apertures, a movable core having a metallic contact on and extending around its outer periphery, means of securing such contact in position, a plunger rod connected at one end to the 95 said removable core, a gland secured to the bottom cover of casing, a connecting rod pivotally attached at one end to the way shaft and at the other end to the said plunger rod, circuit wires connecting the said contact fingers, a bell, a battery and the said dial, contact plates and means of adjusting the movable contact consisting of a turn buckle located in the center of the said connecting rod and adapted to extend or 100 shorten such connecting rod, as and for the purpose specified.

In witness whereof I have hereunto set my hand in the presence of two witnesses.

JAMES AUGUSTUS SULLIVAN.
